UNITED STATES PATENT OFFICE.

GEORGE P. CRAGIN, OF SPOKANE, WASHINGTON.

CUFF-LINK.

1,295,440.

Specification of Letters Patent. Patented Feb. 25, 1919.

Application filed August 13, 1918. Serial No. 249,713.

To all whom it may concern:

Be it known that I, GEORGE P. CRAGIN, a citizen of the United States, residing at Spokane, in the county of Spokane and

5 State of Washington, have invented new and useful Improvements in Cuff-Links, of which the following is a specification.

10 My present invention pertains to cuff-links, and it contemplates the provision of a device for attaching the well-known stiff "four button-hole" cuff, or the "eight button-hole" folded soft cuff, to the wristband of the shirt in such a manner that the cuff may be used as a "link-cuff," reversible after one 15 portion thereof has been soiled.

It is a well-known fact, that with "link-tab" cuffs, such as are at present in use, it is impossible to reverse the cuffs and thereby prolong their cleanly appearance. With the 20 cuffs attached to the shirt, it is necessary to change the shirt after a short period of wear, on account of the cuffs becoming soiled, and it is to overcome these objections that I provide my "novel-link."

25 With the foregoing in mind, the invention will be fully understood from the following description and claims when the same is read in connection with the drawings accompanying and forming part of this specification, in which:

Figure 1, is a view illustrating a portion of a shirt sleeve, wristband and a stiff cuff attached and the "novel-link" to attach said cuff to the wristband of the shirt sleeve.

30 Fig. 2, is a section taken in the plane of the line 2—2 of Fig. 1.

Fig. 3, is a detail view of my preferred "novel-link."

35 Figs. 4, and 5 are views of modified "novel-links."

Referring to said drawings, and particularly to Figs. 1 to 3 thereof:

1, is a shirt sleeve, having the usual wristband 2, and a button hole 5. 4, is the ordinary well-known "four-button-hole" stiff cuff, provided at either end with button-holes for attaching on wristband of shirt sleeve 1, the soft cuff being attached in the same manner.

40 My preferred "novel-link" comprises a ring 6, having a shank 7, of wire or other suitable material. The said shank 7, is constructed at either end so as to form eyes or loops 8 and 9 respectively. The eye 8, securely retains the ring 6, while the eye 9 is for the reception of a button 10, which has a

ring 11 at the back thereof. The said ring 11 is by preference integral with the button 10.

45 In the practical use of my device, the cuff is adjusted in the present well-known manner, after which the ring 6 of the link is passed over the sleeve-button 0 and held in place by buttoning the outer back-button-hole of the cuff onto the said sleeve-button, 50 while the corresponding button-hole of the cuff is held in place by the button 10 of the "novel-link." It will be seen that this will present a neat appearance, thoroughly practical, the "novel-link" invisible, and furthermore the operation can be accomplished, 55 either adjusting or removing, without loss of time or patience.

60 It will be readily appreciated that when using my "novel-link," commercially, it will be necessary for the manufacturer to make only the regular "four-button-hole" stiff cuffs, such as are usually carried by haberdashers in white, or the six or eight-button-hole folded soft cuff, and by applying my 65 "novel-link," two to be furnished with each shirt, the cuffs are immediately changed to reversible, neat-fitting, practical "link-cuffs" which will have double the exposed wearing 70 surface of "tab-cuffs" or those stiff or soft 75 cuffs attached to the shirt.

75 It is also quite an advantage over the well-known "tab-cuff" (one-way), as in the use of said "tab-cuffs," the cuffs usually become soiled long before the shirt, and equally so 80 those cuffs attached to the shirt itself, either the stiff or soft kind in any case requiring extra laundrying and wear and tear.

85 In the modified views of the drawings, I have shown first in Fig. 4, the shank 7, 90 formed of bendable material, and the rings 6' and 10' as integral therewith.

95 In Fig. 5, the shank is shown with a spring hook or semi-ring 14, which springs over the top of the sleeve button, its flexibility holding it in place while the cuff is being 100 buttoned on and serving the same purpose as the ring 6, Fig. 3.

105 It will be gathered from the foregoing, that my "novel-link" in its various designs is simple of construction, inexpensive to produce and contains no delicate parts liable to get out of order.

What I claim and desire to secure by Letters-Patent is:

110 1. As a new article of manufacture, a cuff-link for attaching separate cuff to wristband

of shirt, the combination of a metal shank, a loop formed at one end thereof and a button secured to the opposite end thereof.

2. As a new article of manufacture, a cuff-link for attaching separate cuff to wristband of shirt, the combination of a metal shank, a loop formed of same material and a button having an integral ring at the back thereof, the said shank being provided with eyes whereby the loop may be held at one end

thereof and the button at the opposite end thereof.

In testimony whereof I have hereunto set my hand in presence of two subscribing witnesses.

GEORGE P. CRAGIN.

Witnesses:

W. L. EGGERT,
A. L. BRIGHT.
